(74) Attorney, Agent, or Firm — Fish & Richardson P.C.

(62) Division of application No. 29/378,375, filed on Nov. 3, 2010.

CLAIM

(51) **LOC (9) Cl. 15-03**

The ornamental design for a feeder for a road paving machine, as shown and described.

(52) **U.S. Cl. D15/22; D15/24**

DESCRIPTION

(58) **Field of Classification Search** D15/22-26,

FIG. 1 is a perspective view of a feeder for a road paving machine showing my new design, the bottom view being devoid of surface ornamentation forms no part of the claimed design.

D15/19, 29, 10; 404/110, 101, 108, 118,
404/105, 75, 102, 84.05, 90-92, 84.1, 84.2,
404/84.5, 84.8, 83; 37/18 R, 381, 392, 388

FIG. 2 is a left elevation view of the feeder for a road paving machine of FIG. 1

See application file for complete search history.

FIG. 3 is a right elevation view of the feeder for a road paving machine of FIG. 1.
